UNITED STATES PATENT OFFICE.

EDWARD J. LUPTON, OF CLEVELAND, OHIO.

DESIGN FOR A DOLL.

Application filed November 27, 1922. Serial No. 4,424. Term of patent 3½ years.

To all whom it may concern:

Be it known that I, EDWARD J. LUPTON, a citizen of the United States, and resident of Cleveland, county of Cuyahoga, and State of Ohio, have invented a new, original, and ornamental Design for Dolls, of which the following is a specification, reference being had to the accompanying drawing, forming part thereof.

In said annexed drawing:—

Fig. 1 is a front elevation; and Fig. 2 is a side elevation of a doll showing my new design.

I claim:—

The ornamental design for a doll as shown.

Signed by me, this 24th day of November, 1922.

EDWARD J. LUPTON.
